ELECTRON DISCHARGE DEVICE WITH
TEMPERATURE-STABILIZED CATHODEJerome Kurshan, Princeton, N. J., assignor to
Radio Corporation of America, a corporation
of Delaware

Application April 19, 1949, Serial No. 83,406

6 Claims. (Cl. 250—27.5)

1

This invention relates to electron discharge devices and is particularly concerned with the partial or complete stabilization of the temperature of a bombarded cathode.

A conventional bombarded cathode structure comprises a primary cathode having a thermionic emitting surface for supplying electrons to be utilized in the electron discharge device, and a secondary or auxiliary cathode adapted to emit electrons for bombarding the primary cathode. The primary cathode is maintained at a positive potential with respect to the auxiliary cathode, as a consequence of which bombarding electrons strike the primary cathode and heat it to a temperature which is a function of the instantaneous value of said potential.

In certain applications, for example, in the case of aircraft communications equipment, electrode potentials are subjected to pronounced variations due to variations in the power supply voltage, which, in some cases, may result in cathode temperature variations so extreme as to either render the device temporarily inoperative or shorten tube life, or both.

According to the present invention, the temperature of a primary emitting surface is at least partially stabilized by supplying the bombarding voltage through an appropriate impedance in series with the power supply and the two cathodes, by employing as an auxiliary cathode a thermionic emitter arranged for temperature limited operation, and by supplying energy to the auxiliary cathode at a rate which is a function of the voltage of the power supply.

As a result, changes in the power supply voltage, which would ordinarily result in changes in the velocity of the bombarding electrons and corresponding changes in the temperature of the emitting surface, are accompanied by compensating changes in the rate of electron emission by the auxiliary cathode. Changes in the rate of emission may be considered to be changes in the bombarding current; and since the external path of this current includes an appropriate impedance, changes in the rate of emission will result in compensating changes in the potential drop across the two cathodes.

When the rate at which energy is supplied to the auxiliary cathode varies in the same sense as the power supply voltage, the effect of changes in emission acts in opposition to the effect of changes in the power supply voltage, with the result that the temperature of the primary emitting surface is at least partly stabilized.

The external impedance may have a purely

2

resistive component, or, under some circumstances, it may be desirable to employ a circuit element whose dynamic resistance is greater than its static resistance.

5 According to one embodiment of the invention, the auxiliary cathode is maintained at operating temperature by radiation from the primary cathode, while, according to another embodiment, the auxiliary cathode is heated by an electric current which varies with the voltage of the source which supplies the bombarding voltage between the two cathodes.

10 It is therefore a general object of my invention to eliminate or to reduce changes in primary emitter temperature which would ordinarily result from changes in the bombarding potential difference, by employing as an auxiliary cathode a temperature limited thermionic emitter whose energy input varies in a suitable manner with the power supply voltage.

15 Another object of the invention is to provide an electron discharge device of the bombarded cathode type in which the auxiliary cathode is disposed to be maintained at a temperature appropriate to temperature limited operation by radiation from the primary cathode.

20 Another object of the invention is to stabilize the temperature of the bombarded cathode by supplying energy to an auxiliary cathode at an average rate appropriate to the maintenance of temperature limited operation of said auxiliary cathode, but subject to variations related to variations in the power supply voltage.

25 30 35 Another object of the invention is to stabilize the temperature of a bombarded cathode by operating the auxiliary cathode in the temperature limited portion of its characteristic, the said auxiliary cathode being heated by a heating current supplied by the same source as the bombarding voltage.

40 45 40 How these objects and others which will appear are attained will be seen more fully from the detailed description which follows and from the drawings, in which:

Figure 1 is a perspective view partly in section of an electron discharge device including a first embodiment of the invention in which the auxiliary cathode is maintained at an emitting temperature by radiation from the primary cathode;

Figure 2 is a schematic diagram illustrative of a second embodiment of the invention in which the auxiliary cathode is maintained at an emitting temperature by heating current derived from the same electrical energy source that supplies

the bombarding current to the primary cathode; and

Figure 3 is a schematic diagram illustrating a typical application of the invention to a known type of radio receiver.

In Figure 1, I have illustrated an envelope 1 containing an anode 10, a primary cathode 11 adapted to emit electrons which may be collected by anode 10, and an auxiliary cathode 12 which may be either a directly or indirectly heated thermionic cathode. It will be understood that one or more additional electrodes may be located between anode 10 and cathode 11, such additional electrodes being omitted from Figure 1 for the sake of clarity.

I have also indicated a source 13 of bombarding current and an auxiliary source 14 of current adapted to be connected across the terminals of auxiliary cathode 12 through a switch 15. Source 13 is series connected with a resistance 16 and the internal diode comprising cathode 12 and cathode 11, and provides for maintaining cathode 11 at a positive potential with respect to cathode 12.

Cathode 12 is adapted to be initially brought to emitting temperature by closing switch 15 and thereby connecting source 14 across cathode 12. It will be understood, however, that the initial heating current for cathode 12 may be derived from the main source of cathode power 13.

After cathode 12 reaches emitting temperature, electrons are attracted to cathode 11 by virtue of the positive potential thereon, bombarding and raising cathode 11 to emitting temperature, whereupon the discharge device comprising primary cathode 11 and anode 10 operates in the usual manner.

In addition, cathodes 11 and 12 are so arranged that sufficient heat is radiated inwardly by cathode 11 to maintain cathode 12 at emitting temperature, and, accordingly, switch 15 may now be opened.

Assuming a steady value for the voltage of source 13, both cathodes will be maintained at emitting temperature, and the electron emission from cathode 11 will, of course, be constant.

Now consider the effect of a change in the voltage of the source 13.

If the potential difference between cathode 12 and cathode 11 increases, due to an increase in the voltage of source 13, no increase in electron current from cathode 12 will result directly therefrom, because the cathode 12 is operated in temperature-limited condition. However, the increase in voltage will cause the velocity of electrons striking cathode 11 to increase, raising the temperature of cathode 11 which, at least temporarily, increases the electron emission from cathode 11. At the same time, however, the increase in temperature of cathode 11 is communicated in part by radiation to cathode 12, raising the temperature of the latter and resulting in an increased electron emission therefrom and, hence, an increase in the current in the external circuit 13-16. The increased emission from cathode 12 is produced by the rise in cathode temperature without a further increase in potential difference across the diode, and hence, the effective direct current resistance of the diode is decreased. As a result, when the supply voltage increases, although the diode current and the potential drop across the fixed resistance 16 increases, the fractional increase in the potential drop across the diode is not as great as the fractional increase in the drop across the resistance

16. If the diode potential drop could be made to vary exactly inversely with the diode current the power input to the cathode 11 would be constant, and the temperature of the cathode would be perfectly stabilized. While this ideal condition cannot be fully attained in the embodiment of my invention illustrated in Figure 1, it will be shown that, if the resistance 16 is large compared to the normal diode resistance, the effects of variations in the power source on the diode potential difference, and hence, on the power input to the primary cathode and on the cathode temperature, will be reduced to a minimum.

Upon decrease of cathode operating potential difference, the velocity of electrons striking cathode 11 will decrease, the temperature of cathode 11 will decrease, the temperature of cathode 12 will also decrease, reducing the rate of emission of electrons by cathode 12 and increasing the voltage drop across the diode, as a result of which, again, fractional change in potential drop across the diode will be less than the fractional change in potential drop across the resistance 16.

It will be understood that since cathode 12 is heated by radiation from cathode 11, its temperature will always be lower than that of cathode 11, the difference in temperature being great enough to permit the transfer of sufficient energy to overcome the work function of the material of which the emitting surface of cathode 12 is made. While the two cathode structures may be made of similar materials, it is preferable to form the emitting surface of the cathode 12 of a material having a higher work function than the material comprising the emitting surface of cathode 11, in order that the dependence of the rate of electron emission by diode 12 upon temperature be as great as possible, since it is this factor which ultimately effects the stabilization of the temperature of the emitting surface of cathode 11.

The principal requirement is that the operating temperature of cathode 12 be so related to its work function as to provide for temperature-limited operation within the range of conditions to be met in operation. Since cathode 11 should be maintained at sufficiently high temperature to give space charge limited operation, this means that if cathode 12 is operated at a temperature near the temperature of cathode 11, the work function of the material of cathode 12 must be higher than that of the material of cathode 11. Conversely, if the electron-emitting materials on the two cathodes are the same, the internal cathode should be arranged to operate at a considerably lower temperature than the external cathode. For example, the temperature of cathode 12 relative to that of cathode 11 may be readily controlled by control of the amount of heat conduction to the supports of cathode 12.

Where E_0 is the instantaneous voltage of source 13, and R is the resistance of resistor 16, the power into the cathode 11 is

$$P = i(E_0 - iR) \quad (1)$$

and

$$\frac{\delta P}{\delta i} = E_0 - 2iR \quad (2)$$

From (2) it can be seen that the rate of change of power with current is negative if the D. C. resistance of the inner diode is less than the series resistance 16. Thus, the device will always be self-stabilizing if the internal resistance of the diode is small enough.

The magnitude of the stabilizing action to be

expected in a typical example will be understood from the following. Assume that cathodes 11 and 12 are to be operated at about the same temperature T , and let i be the temperature-limited electron current from cathode 12, and P the electron bombardment power to cathode 11. By the Stefan-Boltzmann equation

$$P = K_1 T^4 \quad (3)$$

and by the Richardson-Dushman equation

$$i = AT^2 e^{-b/T} \quad (4)$$

Setting Equation 1 equal to Equation 3, substituting for i from Equation 4 and dividing through by T^4 , we may define T implicitly as a function of E_0 :

$$F(E_0, T) = AT^{-2} e^{-b/T} E_0 - A^2 e^{-2b/T} R - K_1 = 0 \quad (5)$$

Hence,

$$\frac{dT}{dE_0} = -\frac{\delta F/\delta E_0}{\delta F/\delta T} \quad (6)$$

It is the reciprocal of this quantity which we wish to make large.

Now,

$$T^2 \frac{dE_0}{dT} = 2E_0 T + b(2Ri - E_0) \quad (7)$$

but if cathode 11 were heated by a zero temperature coefficient cathode heater in series with resistor 16,

$$T^2 \frac{dE_0}{dT} = 2E_0 T \quad (8)$$

We wish (7) to be larger than (8), and, accordingly, we require $2Ri > E_0$. That is, the diode plate resistance must be less than the resistance of resistor 16. For economy, let the resistance of resistor 16 be only twice the diode resistance, or

$$Ri = \frac{2}{3} E_0 \quad (9)$$

and

$$T^2 \frac{dE_0}{dT} = 2E_0 T \left(1 + \frac{b}{6T}\right) \quad (10)$$

Now, $b = 11,600 E_w$ (K.), where E_w equals the work function in volts. In an oxide coated emitter, we may take

$$E_w = 1 \text{ volt} \quad (11)$$

$$\frac{b}{T} = 11.6 \text{ at } 1000^\circ \text{ K.} \quad (12)$$

and

$$T^2 \frac{dE_0}{dT} = 2E_0 T \left(1 + \frac{11.6}{6}\right) \quad (13)$$

Equation 13 indicates a reduction in the rate of temperature increase with increase in supply voltage of about 3 as compared with Equation 8.

It will be understood that different degrees of stabilization will be achieved with differing values for resistor 16, and also for emitter materials having different work functions. For example, when employing tungsten for the emissive material of cathode 12,

$$\frac{b}{T} = 22$$

and the reduction factor would be $1 + 22/6$ or about 4 1/3.

It should be understood that during operation of the tube it may not be necessary to disconnect power source 14, if the power derived from source 14 is small as compared with the bombardment power to cathode 11.

A typical example of a miniature receiving tube incorporating this embodiment of the invention may comprise a cathode 11 having inside diameter

of 0.040" and a length of 25 mm., requiring a power input of 1.9 watts. The bombardment current corresponding to this amount of power must be less than the space charge limited current at the operating bombardment voltage, that is, the bombardment current must be less than the current which could be drawn by the bombardment voltage upon an increase in the temperature of the internal cathode. This condition may be met below 30 volts; for example, with a bombardment current equal to 0.1 ampere/cm.², cathode 12 may have the reasonable diameter of .010 inch. It will be understood that cathode 12 may be made larger in diameter and operated at a lower temperature to give the same electron emission.

Turning now to the second embodiment of the invention, I have illustrated in Figure 2 a primary cathode 11a, an anode 10a adapted to collect electrons emitted from primary cathode 11a, and an auxiliary cathode 12a arranged to supply bombarding electrons to cathode 11a. In this case, energy is supplied to cathode 12a in the form of an electric current from a source 13a which also supplies bombarding current to the internal diode comprising the two cathodes. It will therefore be understood that the voltage applied to cathode 12a will vary directly with the voltage of the source 13a which supplies the bombarding current. I have also illustrated in Figure 2 a pair of additional grid electrodes 17 and 18 interposed between cathode 11a and anode 10a, although it will be understood that the electron stream between cathode 11a and anode 10a may be controlled in other ways or that the primary electron stream may be entirely unintercepted.

It will be seen at the outset that qualitatively the embodiment of Figure 2 is capable of an operation similar to the embodiment of Figure 1, that is, the variations in diode resistance produced by changes in the energy input to the auxiliary cathode will oppose changes in bombardment voltage due to changes in the voltage of the bombarding current source. However, the result is produced in somewhat different manner in Figure 2. An increase in the supply voltage E_0 would be expected to increase the potential difference between the two cathodes, and hence, the power to cathode 11a and the temperature thereof. However, the increase in E_0 is also applied directly to auxiliary cathode 12a in this embodiment which increases the temperature of 12a and the rate of emission or current therefrom to the primary cathode. The increased current between the cathodes reduces the diode resistance. The result is that due to the presence of the resistance 16a in series with the diodes the increase in supply voltage is absorbed at least partially by the resistance 16a, and the bombarding potential difference between the cathodes does not increase in proportion to the power supply voltage. Equation 2, which applies also to the embodiment of Figure 2, shows that the resistance 16a should be at least equal to the diode resistance, to produce any stabilizing effect. It will be shown that the resistance can be so chosen that the power input to the primary cathode will be constant, thus effecting perfect stabilization of the cathode temperature.

If the filament of cathode 12a has a zero temperature coefficient of resistance, the power supplied to the filament 12a is

$$P_F = \left(\frac{mE_0}{R_F}\right)^2 = pT_F^4 \quad (14)$$

where m is the fraction of E_0 applied to the fila-

ment, E_0 is the power supply voltage, R_F is the filament resistance at temperature T_F , and p is a constant. With temperature-limited emission from the filament, the bombarding current is

$$i = AT_F^2 e^{-b/T_F} \quad (15)$$

where A and b are the constants of Equation 4. From Equation 14,

$$T_F = qE_0^{1/2} \quad (16)$$

Hence, (15) may be written

$$i = BE_0 e^{-C/E_0^{1/2}} \quad (17)$$

The power to cathode 11a is

$$P_c = iE_0 - i^2 R = BE_0^2 e^{-C/E_0^{1/2}} (1 - BR e^{-C/E_0^{1/2}}) \quad (18)$$

Therefore, by differentiating (18) and substituting back from (17), the rate of change of cathode power to change in supply voltage E_0 , becomes

$$\frac{dP}{dE_0} = 1/2E_0^{-1/2} Ci \left(1 - \frac{2iR}{E_0} \right) + 2i \left(1 - \frac{iR}{E_0} \right) \quad (19)$$

To find the optimum value of the resistance R for stabilizing the cathode temperature, let

$$\frac{iR}{E_0} = x$$

where x is the fraction of E_0 appearing across R , and Equation 19 becomes

$$\frac{dP}{dE_0} = 1/2E_0^{-1/2} Ci (1 - 2x) + 2i(1 - x) \quad (20)$$

For perfect stabilization, dP/dE_0 must be zero, hence

$$\frac{C}{4E_0^{1/2}} (1 - 2x) + 1 - x = 0 \quad (21)$$

For a tungsten emitter,

$$\frac{C}{4E_0^{1/2}} = \frac{b}{4T_F} = \frac{22}{4} = 5.5$$

and substituting in (21), we find that $x = 13/24$, or approximately .54. Therefore, if iR is $13/24E_0$, there is perfect stabilization of the power input into cathode 11a with respect to changes in E_0 . Since $E_0 = iR + iR_D$, where R_D is the normal diode resistance, the optimum value of R is $13/11R_D$, or approximately $1.18R_D$.

Thus, it will be seen that while the stabilization achieved by the arrangement of Figure 1 approaches complete stabilization only as the external resistance becomes much larger than the internal diode resistance, perfect stabilization is achieved in the arrangement of Figure 2 when the external resistance is only slightly greater than the diode resistance. A still further improvement may be achieved if the filament has a negative temperature coefficient of resistance.

In either of the embodiments of Figure 1 and Figure 2, a substantial amount of energy is dissipated in the external resistance. When it is desirable to decrease the amount of energy lost in this manner, the external resistance may take the form of a circuit element whose dynamic resistance is greater than its direct current resistance, in which case the same degree of stabilization can be achieved with a smaller loss of energy in the external resistance.

The invention is applicable, in general, to circuits employing electron discharge devices which must be operated from sources of electrical energy whose output voltages are subject to considerable variation. An example of such an application is illustrated in Figure 3, wherein I have indicated

schematically an aircraft radio receiver of the superheterodyne type.

In Figure 3, I have illustrated by general designations the antenna, R. F. amplifier, mixer, I. F. amplifier, audio amplifier, and reproducer portions of the receiver, and have shown in some detail a local oscillator circuit employing an electron discharge device of the type illustrated in Figure 1.

If, as is customary, the cathode heating power is derived from the main battery of an aircraft electrical system, wide variations in voltage may be encountered. In the circuit of Figure 3, the aircraft battery is illustrated by the source 13.

As a consequence of the operation discussed hereinabove in connection with Figure 1, the effect of variations in the voltage of battery 13 on the temperature of cathode 11a is greatly reduced.

I claim:

1. An electron discharge device of the bombarded-cathode type, comprising a main electron-emitting element and an auxiliary electron-emitting element adapted to temperature-limited operation for supplying bombardment electrons for the main emitting element, in which the auxiliary element comprises an emissive surface having a higher work function than the emissive surface of the main element and in which the auxiliary element is disposed in a position relative to the main element to provide for maintaining the auxiliary element at a temperature approaching the temperature of the main element.

2. In combination, a first thermionic cathode, a second thermionic cathode adapted to temperature-limited operation arranged to supply bombardment electrons for maintaining said first cathode at emitting temperature and disposed to be heated by radiation from said first cathode to a temperature substantially below the temperature of maximum practical emission, and an electrical circuit including said two cathodes and including a source of E. M. F. for maintaining a positive charge on said first cathode sufficiently large to attract all electrons emitted by said second cathode, said circuit including an impedance element having a resistance which is large compared to the plate resistance of the diode comprising said two cathodes.

3. An electrical network comprising an electron discharge device of the type having a bombarded primary cathode and an auxiliary cathode, adapted to temperature limited operation, for supplying bombarding electrons, said network further comprising a single source of electrical energy in series with a resistance element and said cathodes for maintaining said primary cathode at a positive potential with respect to said auxiliary cathode and connected to said auxiliary cathode for delivering electrical energy to said auxiliary cathode at a rate proportional to the instantaneous value of the potential applied to said resistance element and said cathodes, the resistance of said element being at least equal to the plate resistance of the diode comprising said two cathodes.

4. An electrical network comprising an electron discharge device of the type having a primary cathode adapted to be maintained at a temperature appropriate to space charge limited operation by electron bombardment, and an auxiliary cathode, adapted to temperature-limited operation, for supplying bombarding electrons, in combination with a resistance element, a source of electrical energy in series with said resistance element and said cathodes for maintaining said

primary cathode at a positive potential with respect to said auxiliary cathode, and means for delivering electrical energy to said auxiliary cathode from said source at an average rate appropriate to the maintenance of said auxiliary cathode in temperature-limited operation, the resistance of said element being substantially greater than the plate resistance of the diode comprising said two cathodes.

5. An electrical network comprising an electron discharge device of the type which comprises a primary cathode adapted to be maintained at emitting temperature by bombardment with electrons from an auxiliary cathode adapted to temperature-limited operation, said network 10 comprising in combination with said device an electrical circuit for maintaining the primary cathode at a positive potential with respect to the secondary cathode, said circuit including a source of E. M. F. and a resistance greater than 20 the internal resistance of the electron path between said cathodes, and a source of electrical energy for delivering power to said auxiliary cathode.

6. An electrical circuit comprising an electron discharge device of the type having a primary cathode adapted to be maintained at emitting temperature by electron bombardment and an auxiliary cathode adapted to temperature-limited operation for supplying bombarding electrons, in 25 combination with an impedance element having a resistance at least equal to the plate resistance

of the diode comprising the two cathodes, a first source of electrical energy connected in series with said impedance element and said diode for maintaining said primary cathode at a positive potential with respect to said auxiliary cathode, and a second source of electrical energy connected to said auxiliary cathode for producing temperature-limited emission therefrom, whereby changes in the temperature of said primary cathode produced by variations in the voltage of said first source are reduced.
